JUSTUS B. ENTZ, OF CLEVELAND, OHIO, ASSIGNOR TO EDWIN L. THURSTON, TRUSTEE,
OF CLEVELAND, OHIO.

STARTING AND REVERSING MEANS FOR INTERNAL-COMBUSTION ENGINES.

1,208,113.

Specification of Letters Patent. Patented Dec. 12, 1916.

Application filed December 23, 1912. Serial No. 738,122.

To all whom it may concern:

Be it known that I, JUSTUS B. ENTZ, a citizen of the United States, residing at Cleveland, in the county of Cuyahoga and 5 State of Ohio, have invented a certain new and useful Improvement in Starting and Reversing Means for Internal-Combustion Engines, of which the following is a full, clear, and exact description.

10 This invention relates chiefly to starters for internal combustion engines, and has for its principal object to provide in connection with an internal combustion engine, mechanism by which the engine may be started and operated in either direction. In other words, the invention in one of its aspects 15 contemplates a reversible internal combustion engine having an operative relationship therewith, a reversing or reversible starter. 20 A still further object is to associate with or incorporate in the starter-operating member, a magneto short circuiting switch so arranged that when the starter is in operation, the short circuiting switch is rendered inoperative, or is opened, and when the starter-operating member,—in this case an electric switch, is moved from a position for forward engine movement, to a position for reverse starting and drive, the ignition system is 25 30 thrown out of operation by short circuiting the magneto.

My invention may be briefly summarized as consisting in certain novel combinations and arrangements of parts and details of 35 construction which will be described in the specification and set forth in the appended claims.

In the accompanying sheets of drawings, wherein I have shown one embodiment of 40 my invention which operates with high efficiency, Figure 1 is a side elevation, with parts in section, of an internal combustion engine provided with a starter controlling and also with cam shaft shifting mechanism 45 by which the engine may be started by the starter and will operate in either direction; Fig. 2 is a face or front view of the starter switch and part of the cam shaft shifting mechanism; Fig. 3 is a detail sectional view 50 substantially along the line 3—3 of Fig. 2, looking in the direction indicated by the arrow; Fig. 4 is a similar view substantially along the line 4—4 of Fig. 2; Fig. 5 is a diagrammatic view showing particularly 55 the storage battery, the starter controlling

switch, the magneto, and various electrical connections; Fig. 6 is a diagrammatic view showing the effective connections and circuits which are established when the starter switch is thrown to a position for starting 60 and for engine operation in a forward direction; Fig. 7 is a similar view of the connections which are established when the starter switch is thrown into position for reverse starting and operation; Fig. 8 is a 65 simple conventional view of the engine and starter.

Referring to the drawings, 10 represents the internal combustion engine which is adapted to be started in either direction by 70 the starter, and to operate or drive in either direction after it is started. The starter which I prefer to employ for this purpose is a reversing electric motor, or dynamo motor 11, as the dynamo electric machine is 75 adapted to serve as a generator for lighting or battery charging purposes after the engine is started.

The dynamo motor may be coupled to the engine in any suitable manner. A single 80 permanently connected power transmission agency 11^a, is all that is utilized for forward and reverse starting and for operating the starter as a generator.

For the control of the starter 11, I employ a starter switch 12, which when in one position, connects the motor 11 to the battery 13, so that the motor is started in forward direction, and so as to start the engine for operation in a forward direction, and 90 when thrown into its reverse position, so connects the motor to the battery that the motor is started in the reverse direction, thus causing the engine to be started in the reverse direction. 95

In order that a four-cycle engine, such as I have shown in the drawing, may be operated in both directions, I provide the engine with an endwise shiftable cam shaft 14 having two sets of valve operating cams 14^a 100 and 14^b, one set being adapted to operate the valves and to cause the valves to function in the required manner for forward engine operation, and the other set serving to operate the valves and to cause them to function in the required manner for engine operation in the reverse or backward direction. A spring 15 normally holds the cam shaft 105 in its right hand position as the same is viewed in Fig. 1, so that the set of cams 14^a 110

will be in position to operate the valves. I provide also between the cam shaft and the starter operating switch 12, a suitable connection which causes the cam shaft to be shifted against the pressure or tension of the spring 15 when the switch is thrown to its reverse position. This connection or connecting mechanism includes an arm 16 which is carried by a shaft 17, which on being rocked in one direction, causes the arm 16 to move the cam shaft to the left, or to the position for reverse engine operation so as to move the cams 14^b to operative relationship with respect to the valve stems. The shaft 17 is connected to the movable part 12^a of the switch 12, the connection including an arm 18 secured to the shaft 17, a link 19 composed of two parts yieldably connected by a spring 19^a, and one part attached to the arm 18, and the other to a crank 20 connected to the movable switch member.

When the switch is moved from off position to its upper position, the engine is started by the motor forwardly and operates in a forward direction, and when the switch is thrown to its reverse position, the cam shaft is shifted, the motor is started in a reverse direction, and the engine starts and operates in a reverse direction. The two-part link 19 and the spring connecting the parts thereof allow the switch 12 to be thrown to reverse position, even though the positions of the cams might prevent the cam shaft being at the same time shifted to the left or to the position for reverse operation. However, if the cam shaft can not be shifted just at the time the switch is thrown, it will be shifted by the spring 19^a as soon as the motor starts to turn over the engine or as soon as the cam shaft is turned slightly. It will be understood of course that the magneto which is used as a source of current for ignition purposes will give a spark at the desired degree of advance for either direction of rotation. The latter, however, includes simply a matter of magneto design, which we believe need not be here described in detail.

Referring now to the diagrammatic views especially Figs. 5, 6 and 7, it will be seen that the dynamo motor 11 includes an armature 11^a, a series field winding 11^b, and a shunt field winding 11^c. The terminals of the armature and field windings of the dynamo motor and the terminals of the battery are connected to terminals of the double throw switch 12 by suitable conductors 21. It is believed to be unnecessary, however, to describe in detail the various connections.

When the switch is thrown to its upper position, to start the engine forwardly, the parts are connected as shown in Fig. 6. The battery now supplies current to the dynamo

series and shunt field windings, in a direction such that the fields are additive, thus producing maximum field strength.

The switch remains in the upper or forward position after the engine is started, and while the electrical connections shown in Fig. 6 are unaltered until the switch is again opened. After the engine picks up in speed, the dynamo motor is driven as a generator to charge the battery or to supply current to the lighting circuit 22. When the machine changes from a motor to a generator, the current reverses in the series field winding, and this decreases the field strength an amount dependent upon the value of the current in the series winding, and hence on the speed at which the machine is driven. Therefore, the current in the series winding has a regulating action, causing the generator to serve as a substantially constant voltage machine.

When the starter switch is thrown to its reverse position, the connections shown in Fig. 7 are made. By referring to this figure, it will be seen that the shunt field winding is cut out of service, and that the current in the armature is reversed so that the direction of rotation of the motor is reversed with respect to the direction of rotation when the switch is thrown to its forward position. This of course, starts the engine in the reverse direction, particularly as the cam shaft is shifted as before stated. After the engine picks up in speed, in the reverse direction, the dynamo motor will not generate current in view of the fact that the shunt winding is disconnected or on an open circuit. If desired, however, I may use the dynamo motor as a generator when the engine is operating in the reverse direction, but under ordinary circumstances, the engine will operate in the reverse direction for short intervals of time as compared with operation in the forward direction, and as it is not essential that the dynamo motor be used for battery charging purposes, during the periods of reverse drive, I employ a switch which disconnects the shunt field winding when the switch is in reverse position, as I am thus enabled to use a simpler switch than would otherwise be required.

By reference to Figs. 1, 2 and 5, it will be seen that the magneto switch or short circuiting switch of the magneto 23 is incorporated in the main starter switch 12. One terminal of the grounding or short circuiting circuit 23^a of the magneto is connected to a contact 24 of the switch 12, which has adjacent the contact 24, a second contact 24^a which is grounded as shown, (see Figs. 2, 3, 4 and 5). These two contacts 24 and 24^a are sufficiently near each other that when the movable member of the switch 12 is in its off position or full open, one of the blades

of the switch passes between and electrically connects the two contacts 24 and 24^a so as to short circuit or ground the magneto. When, however, the switch is in either of its 5 operative positions for forward or reverse drive, the blade of the switch passes from between the contacts 24 and 24^a so as to open the magneto short circuit or ground. This arrangement has numerous advantages, 10 among which may be mentioned—it does away with the liability of premature ignition being caused in a cylinder while the engine is being turned over by the starter, such as might result if the operator were 15 able to open and close the short circuit of the magneto with a short circuiting switch not mechanically connected to or operatively associated with the starter switch. A second result obtained with the present arrangement is that the ignition system is 20 thrown out of operation so as to stop the engine when the starter switch is moved from one operative position to its other operative position,—that is to a position for 25 drive in one direction to a position for drive in the opposite direction. A third advantage lies in the fact that the operator cannot stop the engine by closing the short circuiting switch without opening the starter switch. 30 Having thus described my invention, what I claim is:

1. In combination, a reversible valve internal combustion engine having a shiftable valve operating means whereby the valves 35 may be operated for either forward or reverse drive, a starter, together with means for transmitting power from the starter to the engine for starting the engine in either direction, and a unitary means having pro-

40 gressive operative positions for controlling the direction of drive of the starter, and for controlling the shifting of the valve operating means.

2. In combination, a reversible valved internal combustion engine, shiftable valve operating means adapted to operate the 45

valves for engine drive in either direction, a reversible starter together with means for transmitting power between the starter and engine for starting the latter in either direction, a starter operating member controlling the direction of starting, and an operative connection between said member and the shiftable valve operating means. 50

3. In combination, a reversible valved internal combustion engine adapted to drive in either forward or reverse direction, shiftable valve operating means for operating the valves for either direction of drive, a reversible electric motor coupled to the engine, a switch for controlling the direction of rotation of the motor, and connecting means between said switch and the shiftable valve operating means, for shifting the valve operating means when the switch is thrown 60 to position for starting in reverse direction. 65

4. In combination, a reversible internal combustion engine, a starter for starting the engine in either direction, a starter controlling member having two operative positions and an intermediate inoperative position, means for supplying igniting current to the engine, said starter controlling member having means for cutting out of service the ignition means when said member is in inoperative position. 70

5. In combination, a reversible internal combustion engine, a starter for starting the engine in either direction, a starter controlling member having two operative positions, and an intermediate inoperative position, a source of igniting current, said starter controlling member having means for cutting said source out of service in passing from 85 one operative position to the other. 80

In testimony whereof, I hereunto affix my signature in the presence of two witnesses.

JUSTUS B. ENTZ.
